Primary Examiner — Sheryl Lane*Assistant Examiner* — Samantha N Wood(74) *Attorney, Agent, or Firm* — Hankin Patent Law, APC; Kevin Schraven; Anooj Patel(57) **CLAIM**

The ornamental design for the replacement heel pedestal, as shown and described.

DESCRIPTION

FIG. 1 is a top perspective view of a replacement heel pedestal showing my new design.

FIG. 2 is a bottom perspective view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is a rear elevational view thereof; and,

FIG. 8 is a front elevational view thereof.

The broken lines showing connector holes, connectors, and grip pattern are for the purpose of illustrating environmental structure and unclaimed subject matter and form no part of the claimed design.

1 Claim, 8 Drawing Sheets(56)
